UNITED STATES PATENT OFFICE

21,643

INTERGEARED OFFSET DISK HARROW

Jacob V. Dyrr, Bell, Calif., assignor to International Harvester Company, Chicago, Ill., a corporation of New Jersey

Original No. 2,164,204, dated June 27, 1939, Serial No. 753,877, November 20, 1934. Application for reissue June 27, 1940, Serial No. 342,829

28 Claims. (Cl. 55—83)

This invention has to do with the type of ground working implement that is shown in my issued Patents 1,916,720 and 1,916,721, dated July 4, 1933; and the general object of the invention is to provide, for that general type of device, an improved arrangement and means for angling, and controlling the angling of, the plurality of gangs which are characteristic of this type of device.

In, for instance, my prior Patent 1,916,721 I have shown a harrow comprising two gangs of disks, intercoupled to swing or angle relative to each other, and so coupled to draft means that the draft, in cooperation with the soil drag, tends to angle the gangs. In the arrangement there shown, the draft means is coupled to the forward gang at one side, and to the rear gang at the other side; and the two gangs are intergeared so that angling of one gang tends also to angle the other. For positively angling the gangs into certain positions, for instance, for a right-hand turn, and for controlling the anglings in that and certain other positions, I have provided a control line which, being attached to the tractor at an offset point at one side, is connected to the rear gang at the opposite side, and at the side of that rear gang opposite to that at which the draft is coupled to the rear gang.

In my present arrangement I couple such a control line to the forward gang rather than to the rear gang, and at the same side of the forward gang as that at which the draft is coupled to the rear gang. And also, in coupling such control line to the forward gang I provide a means whereby, under the control and operation of this control line, the rear gang's draft connection may be locked in various positions relative to the front gang; and thus I provide in a simple and effective arrangement not only an angling and angling control line going directly to the front gang, but also a gang locking means actuated automatically by such control line.

The invention will be better understood from a consideration of an illustrative and preferred form of embodiment set out in the following description and in the accompanying drawings in which:

Figure 1 is a plan showing a typical two-gang disk harrow equipped with my present improvements;

Figures 2, 3 and 4 are sectional details on lines 2—2, 3—3 and 4—4, respectively of Figures 1, 2 and 1;

Figures 5, 6 and 7 are diagrams illustrating

typical positions assumed by the harrow in operation;

Figures 8, 9 and 10 are enlarged details showing positions of the control and locking devices corresponding respectively to the positions of Figures 5, 6 and 7.

Referring first in a general way to Figure 1, I show there a two-gang disk harrow of the same general type as shown in my Patent 1,916,721, including a forward gang of disks with a gang frame 10 and a rear gang of disks with a gang frame 11. These two gangs are interconnected so that they may swing relative to each other, and preferably, as in my former patents, I intergear the two gangs by means of meshing gear segments 12 and 13 which are mounted respectively on the two-gang frames, and by a radius bar 14 pivoted to the two frames at 15 and 16 at the centers of the two-gear segments. Gear confining plates 17 and 18, above and below the gears, are mounted on and carried by the radius bar 14; and a locking mechanism, generally designated by the numeral 20 and operated by handle 21 and pull cord 22, is mounted upon the upper plate 17 to lock into notches such as 23 provided in the bracket 24 that carries the rear gear segment on the rear gang frame 11. The details of this locking mechanism need not here be explained as they are explained fully in my Patent 1,916,721, to which reference is hereby made.

Such a locking device may be used for locking, and for limiting the relative anglings of the gang, in connection with the locking control devices which are hereinafter explained, or those herein-after explained may be used solely and without the control and locking device 20. Also, for limiting the anglings of the gangs in certain positions I may further use another arrangement shown in by said prior patent. It will be understood plates 17 and 18, being carried by radius bar 14, move relative to the gear segments and to the brackets 24 and 25 which carry them. The plates may thus be provided with holes 26 into which a pin 27 may be dropped; and that pin, in such angling positions as shown in Figure 5, will come into contact with bracket portion 25a and thus operate as another limit to gang angling.

In Figures 2 and 3 I show my present preferred form of bearing and bearing mounting for the disk shafts. The disk shaft 30 as shown is square, the disks 31 fitting the square shaft. Fitted upon the square shaft is a bearing sleeve 32, having a stepped cylindric exterior bearing surface which fits in the bearing block 33. A flange 34 at the

- larger end of the bearing sleeve bears against a disk 31. Another flange 35, fitted on the smaller end of the bearing sleeve fits the shaft and bears endwise against the next disk 31. End thrust 5 is taken at the step shoulder 32a of the bearing sleeve. The bearing sleeve 32, with its flange 34 and flange disk 35 is thus a spacer between two adjacent disks. The bearing sleeve 32 is cored out, and fits the shaft only at its flanged end 34. 10 At its smaller end it fits into flange plate 36, which fits the shaft.
- Bearing block 33 is pivotally supported by horizontal trunnions 36 in a yoke 37, and the yoke has a vertical pin 38 that has bearing in 15 a bearing bracket 39 secured to the gang frame. By such a bearing structure the disk shafts are mounted in universally movable bearings, which prevents all binding which might otherwise be due to either inaccuracies of workmanship or 20 bending or warping of the frame and other parts. The structure lends itself very readily to construction not requiring great accuracy, and is very much conducive to long life and low friction of the bearings.
- 25 Between other adjacent disks 31, spacer sleeves 32b are fitted on the shaft; and the whole shaft-disk assembly is held together by being endwise confined, as by nut 32c and washer 32d at the shaft end. Such nut and washer may be used 30 at both shaft ends, or at one end of the shaft the confining shoulder may be a permanent head.
- In such harrows as I am here describing, the arrangement is usually such that the harrow trails the tractor in an offset position, the disks of the 35 front gang usually being concave toward the right and those of the rear gang concave toward the left. For the purposes of simplicity in this description I shall therefore describe the draft and angling control devices as they are in practice 40 applied to the gangs at right and left, respectively, but without necessary limitation of the invention to those relative transverse directions. I may also note that the intergearing of the two gangs is preferably somewhat to the left of the 45 center of the gangs, and that the gear section 12 of the rear gang preferably is of smaller radius than gear 13 of the forward gang, so as to cause the angling movement of the rear gang to angle the forward gang, rather than vice versa.
- 50 I will thus proceed to describe the draft and angling devices, using the terms "right" and "left" as they appear to an observer standing behind the harrow and facing forward toward the tractor.
- 55 The draft is coupled to the forward gang at the right-hand front corner, through a universally flexible clevis 40. The draft frame is made up of a primary draft bar 41, adjustable in length; a secondary draft bar 42 also adjustable in 60 length; and a spreader bar 43. Bars 41 and 43 are pivoted together at 44 to the draft clevis 40, bar 42 is pivotally connected at 45 to the forward end portion of bar 41; and the two bars 42 and 43 are connected together at the pivot 46 where coupling is made to the universal clevis 47 to which the rear gang draft bar 48 is connected. This draft bar 48 connects pivotally, that is flexibly, at 48 with the left-hand side of the rear gang frame.
- 65 Draft bar 48 passes through a slot 58 in a vertical plate 51 mounted on the front of the forward gang frame 10. Bar 48 may preferably be rectangular in cross section, and the slot 58 is of such size as to freely pass the rod and to allow 75 for its transverse change of position relative to

the front frame. Plate 51, in addition to being a guide for bar 48, performs the office of a stop which limits the rearward movement of bar 48 in positions similar to that shown in Figures 6 and 9. In a position just beyond that shown in 5 these figures the clevis 47 will move back against plate 51 and thus may act to limit angling positions such as are shown in Figure 6.

Slidable on bar 48 behind plate 51 is a lock block 53. This block is preferably tubular in 10 form, large enough that it cannot pass through the plate slot 58, and it carries a locking pin 54 adapted to enter any one of a number of longitudinally spaced holes 55 in bar 48. This pin 54 is carried by arm 56 of a small bell crank lever 15 pivoted on the lock block, the other arm 57 of the lever having a spring 58 and a pull cord 59 connected to it. Pull cord 59 extends forward to the tractor to be within easy reach of the operator. Tension spring 58 is connected at its other end to 20 the block 53, so that the spring always tends to move lock pin 54 into any hole 55 which comes into register.

Extending forwardly from lock block 53, and 25 normally projecting forwardly through stop plate 51 is a latch tongue 60 having on its forward end a projecting latch lug 61. In the normal position of the lock block and the latch, the lug 61 is engaged from behind by a latch pawl 62 pivoted at 63 on the left-hand side or end of frame 10. 30 This pawl is normally moved into position to engage behind the latch lug by a spring 64; and, as will readily be seen from Figure 8, for instance, the latch pawl engages behind lug 61 when block 53 is in its forward position against plate 51. 35 Thus, in such a position of the parts, if the block 53 is then locked by pin 54 to bar 48, the bar 48 is held immovable relative to the front gang and consequently the two gangs are relatively locked 40 against changes of angle. Retraction of pin 54 by pulling on line 59 will at any time release bar 48 from the lock block and allow the gangs to 45 change angle.

Latch pawl 62 has an eye 65 to which the rear 50 end of the angling and control member 66 is attached. This member, here shown as a chain, has its forward end attached to a member 67 of the draft bracket which is mounted on the tractor T. This draft bracket may be made up in any suitable manner to provide for coupling 55 member 66 at a laterally offset point. As shown in the drawings, the draft bracket may be made up of a draft member or draw-bar 68, to which the draft bar 41 is pivotally, flexibly, attached at 69, preferably on the center line of the tractor. And the draft bracket may include the bracket member 67 which extends out to the left and has in it a plurality of spaced holes 70 to which the forward end of chain 66 may be selectively connected, as by an S-hook 71 which may be hooked 60 into any hole and hooked into any chain link. The length of member 66 thus may be made adjustable, as also the lateral offset of its coupling to the tractor.

The leg 61, the pawl 62, and the spring 64 constitute 65 release means act directly on the front gang 10.

The rear gang draft bar 48, the block 53, and the latch pawl 62 constitute means for holding the harrow gangs against relative angling movement. The pawl 62 mounted at 63 on the frame 10 may be considered a release means mounted on the forward harrow gang for releasing the gangs so that they are permitted relative angling movement.

Figure 1 shows the implement in the position used when being transported without doing any work. In this position the gangs are substantially parallel and the planes of the disks are substantially directly fore and aft, so that they will not dig into the surface on which they roll. The gangs are locked in this position by the lock block and latch, as will be readily understood from Figure 1. In this position, with the tractor 10 pulling substantially straight ahead, control chain 66 is slack as is indicated in Figure 1.

When it is desired to put the implement to work, lock block 53 is released by pulling on cord 59, and the two gangs then automatically take 15 such a working position as shown in Figure 7. In taking this position the left-hand end of forward gang 10 moves relatively rearwardly, and carries the block 53 rearwardly along draft bar 48. When the parts have reached such a working position 20 as shown in Figures 7 and 10, the slack in chain 66 has not been sufficiently taken up to pull latch pawl 62 out of engagement with lug 61; the lock block still remains locked to the front frame although bar 48 has been released. In this working position the control chain may be nearly taut, but the pawl 62 still holds lug 61, and consequently block 53 is still held up against stop plate 51. Consequently, after the gangs have reached 25 their working angle, release of cord 59 will allow pin 54 to enter a hole 55 in draft bar 48 and thus 30 lock the gangs in their angled working positions.

When the tractor makes a turn to the right, chain 66 is pulled taut, and latch pawl 62 is immediately pulled out to the relative position 35 shown in Figures 6 and 9. This releases the left end of the forward gang from draft bar 48, and further forward pulling on chain 66 as the tractor turns to the right pulls the left end of the front gang forwardly until the parts have reached such 40 a relative position as shown in Figures 6 and 9. For this operation the lock block 53 need not be released from draft rod 48 and it may therefore travel relatively rearwardly with the rod 48 in such a position as shown in Figure 9. With the 45 gangs in the relative positions shown in Figure 6, no lock is needed as long as the tractor continues to turn to the right; as, in this position, the gang angles are held by the combined actions of the draft means and the control chain 66.

In the position for right-hand turn explained 50 in the last paragraph, the rear gang has moved up, relatively forwardly, on the forward gang. In the normal working position of Figure 5 the rear gang is angled back, and the locking arrangements hold it in that relative angled position, angularly spaced from the front gang. When pawl 62 is withdrawn by the pull on chain 66, releasing lock block 53, the rear gang is then no longer held in angular spacing from the front 55 gang, but can and does move forward and close up on the front gang.

If from the right-hand turn position it is desired to go again into working position of Figures 7 and 10, the block 53 which has not been disturbed in its position on rod 48 will automatically move forwardly to its position of Figure 10, and chain 66 then being slack, pawl 62 will automatically reengage the latch lug 61. If, on the other hand, block 53 has been released from rod 48 70 for any reason, a forward pull on cord 59 will always hold the locking pin 54 up and slide the block 53 forwardly along the rod until it reaches the position of Figure 10 where pawl 62 can engage the lug. Release of cord 59 then engages 75 the locking pin 54 to lock the parts in position.

On making a left-hand turn the rear gang 11 tends to drag behind and thus tends to increase its angle and also to increase the opposite angle of front gang 10. The result of these actions is relatively to move the left-hand end of the rear gang forwardly, and the left-hand end of the forward gang rearwardly, so the parts tend to take such a position as shown in Figures 5 and 8. The selected point of tractor attachment of chain 66 is such that the left-hand turning of the tractor will keep chain 66 slack, or increase its slack, as the left-hand end of the forward gang drops relatively rearwardly. 5

The left-hand turn can be, and usually is, made in the working position of Figures 7 and 10. 15 If, however, it is desired to increase the angles, either for working or left-hand turning, it is only necessary to pull on cord 59.

In order to allow the increased angling of the gangs to such a position as shown in Figures 5 20 and 8, the lock pin 54 is withdrawn by pulling on cord 59, which allows draft bar 48 to slide relatively forwardly through lock block 53; but the lock block is still held in position by pawl 62 engaging lug 61. When the gangs have reached 25 a suitable left-hand turning position lock pin 54 may be released to again lock the block 53 to rod 48; and the gangs may thus be locked in a left-hand turning position in which they will also effectively cultivate the soil. 30

I claim:

1. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, and an angling control member connected to the tractor at a point offset laterally from the point of draft connection thereto and directly to the forward gang at a point offset laterally to the last mentioned side of the gang interconnection. 35

2. A tractor-operated ground-working implement comprising forward and rearward gangs of ground-working tools, means interconnecting the gangs for relative angling movement in a horizontal plane, draft means flexibly connected to the tractor and embodying draft members severally flexibly connected to the forward gang at one side of the gang interconnection and to the rear gang at the other side of the interconnection, the rear-gang-connected member being 40 movable relative to the forward gang, an angling control member connected to the tractor at a point offset laterally from the point of draft connection thereto and to the forward gang at a point offset laterally to the last mentioned side of the gang interconnection, and stop means acting 45 between the rear gang draft member and the forward gang and controlled by the control member. 50

3. A tractor-operated ground-working implement comprising forward and rearward gangs of ground-working tools, means interconnecting the gangs for relative angling movement in a horizontal plane, draft means flexibly connected to the tractor and embodying draft members severally flexibly connected to the forward gang at one side of the gang interconnection and to the rear gang at the other side of the interconnection, the rear-gang-connected member being 55 movable relative to the forward gang, an angling 60 control member connected to the tractor at a point offset laterally from the point of draft connection thereto and to the forward gang at a point offset laterally to the last mentioned side of the gang interconnection, and stop means acting 65 between the rear gang draft member and the forward gang and controlled by the control member. 70

3. A tractor-operated ground-working implement comprising forward and rearward gangs of ground-working tools, means interconnecting the gangs for relative angling movement in a horizontal plane, draft means flexibly connected to the tractor and embodying draft members severally flexibly connected to the forward gang at one side of the gang interconnection and to the rear gang at the other side of the interconnection, the rear-gang-connected member being 75 movable relative to the forward gang, an angling 75

control member connected to the tractor at a point offset laterally from the point of draft connection thereto and to the forward gang at a point offset laterally to the last mentioned side of the gang interconnection, and means adapted to lock the rear gang draft member to the forward gang and controllable by hand and by the control member.

4. A tractor-operated ground-working implement comprising forward and rearward gangs of ground-working tools, means interconnecting the gangs for relative angling movement in a horizontal plane, draft members flexibly connected to the tractor and to the forward gang at one side of the gang interconnection and to the rearward gang at the other side of the interconnection, the draft member connected to the rearward gang being movable relative to the forward gang, a control member connected to the tractor at a point laterally offset from the point of draft connection thereto and connected to the forward gang at the last mentioned side of the gang interconnection, and stop means acting between the rear gang draft member and the forward gang controllable by the control member.

5. A tractor-operated ground-working implement comprising forward and rearward gangs of ground-working tools, means interconnecting the gangs for relative angling movement in a horizontal plane, draft members flexibly connected to the tractor and to the forward gang at one side of the gang interconnection and to the rearward gang at the other side of the interconnection, the draft member connected to the rearward gang being movable relative to the forward gang, a control member connected to the tractor at a point laterally offset from the point of draft connection thereto and connected to the forward gang at the last mentioned side of the gang interconnection, the draft member connected to the rearward gang including a draft bar, a lock block slidable on the bar, manually controlled means for locking the block to the bar, and means for locking the block to the forward gang and controlled by the control member.

6. A tractor-operated ground-working implement comprising forward and rearward gangs of ground-working tools, means interconnecting the gangs for relative angling movement in a horizontal plane, draft members flexibly connected to the tractor and to the forward gang at one side of the gang interconnection and to the rearward gang at the other side of the interconnection, the draft member connected to the rearward gang including a draft bar movable relative to the forward gang, a latch pawl movably connected with the forward gang at the last mentioned side of the gang interconnection, a lock block slidable on said draft bar, manually controlled means to lock the block to said bar, means engageable by the pawl to hold the block against movement relative to the forward gang, and a control member connected to the tractor at a point laterally offset from the point of draft connection thereto and connected to the pawl to move it to release the block.

7. A tractor-operated ground-working implement comprising forward and rearward ground-working tools flexibly connected with one another, draft means flexibly connected to the tractor and embodying draft members one of which is connected adjacent one end of the forward gang and the other of which is connected

adjacent the other end of the rearward gang and passes over the forward gang adjacent the other end, an angling control member connected to the tractor at a point offset laterally from the point of draft connection thereto and to the forward gang at a point adjacent the portion over which passes the draft member connected to the rear gang, and stop means acting between the rear gang draft member and the forward gang and controlled by the control member.

8. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, means for holding the gangs against relative angling movement, said means including a release means mounted on the front gang, and means connecting the release means and the tractor at a point offset laterally from the point of draft connection thereto for causing a turn of the tractor away from the side to which the said point is laterally offset from the draft connection to cause the release means to release the holding means to permit relative angling movement between the gangs.

9. In combination, a disk harrow comprising two gangs connected for relative horizontal angular movement, draft means for drawing the harrow, means connecting the draft means and a point on one gang on one side of the connection of the gangs and a point on the other gang on the other side of the connection of the gangs, means for holding the gangs against relative horizontal angular movement and including release means mounted on the front gang, and means connecting the draft means and the release means and responsive to turning of the draft means for actuating the release means.

10. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, and means connecting the tractor and the forward gang at a point offset laterally to the last mentioned side of the gang interconnection and responsive to turning of the tractor for exerting a pull upon the front gang to permit the gangs to follow the tractor in making a turn.

11. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, and means connecting the tractor and the forward gang and responsive to turning of the tractor for exerting a pull upon the front gang to permit the gangs to follow the tractor in making a turn.

12. A tractor-operated ground-working implement comprising forward and rearward gangs of ground-working tools, means interconnecting the gangs for relative angling movement in a

horizontal plane, draft means flexibly connected to the tractor and to both gangs, being connected to the forward gang at one side of the gang interconnection and to the rearward gang at the 5 other side of the interconnection, means for holding the gangs against relative angling movement including a release means mounted on the front gang, and an angling control member connected to the tractor and to the forward gang 10 and the release means and operative upon turning of the tractor to actuate the release means to permit the gangs relative angling movement and to exert a pull on the front gang to permit the gangs to follow the tractor in making a turn.

15 13. A tractor-operated ground-working implement comprising forward and rearward gangs of ground-working tools, means interconnecting the gangs for relative angling movement in a horizontal plane, draft means flexibly connected 20 to the tractor and embodying draft members severally flexibly connected to the forward gang at one side of the gang interconnection and to the rear gang at the other side of the interconnection, the rear-gang-connected member being 25 movable relative to the forward gang, an angling control member connected to the tractor and to the forward gang at a point offset laterally to the last mentioned side of the gang interconnection, and stop means acting between the rear 30 gang draft member and the forward gang and controlled by the control member, the angling control member being operative upon turning of the tractor to release the stop means and to exert a pull upon the front gang so as to permit 35 the gangs to follow the tractor in making a turn.

14. A tractor-operated ground-working implement comprising forward and rearward gangs of ground-working tools, means interconnecting the gangs for relative angling movement in a 40 horizontal plane, draft members flexibly connected to the tractor and to the forward gang at one side of the gang interconnection and to the rearward gang at the other side of the interconnection, the draft member connected to the 45 rearward gang being movable relative to the forward gang, a control member connected to the tractor and to the forward gang at the last mentioned side of the gang interconnection, the draft member connected to the rearward gang 50 including a draft bar, a lock block slidable on the bar, manually controlled means for locking the block to the bar, and means for locking the block to the forward gang and controlled by the control member upon turning of the tractor.

55 15. A tractor-operated ground-working implement comprising forward and rearward gangs of ground-working tools, means interconnecting the gangs for relative angling movement in a 60 horizontal plane, draft means flexibly connected to the tractor and to both gangs, being connected to the forward gang at one side of the gang interconnection and to the rearward gang at the other side of the interconnection, an angling 65 control member connected to the tractor at a point offset laterally from the point of draft connection thereto and directly to the forward gang at a point offset laterally to the last mentioned side of the gang interconnection, means 70 for holding the gangs against relative angling movement and including a release means, and means connecting the angling control member and the release means.

75 16. The device specified in claim 15, the release means being mounted on the forward gang.

17. In a tractor-drawn offset harrow, two gangs connected for relative horizontal angular movement, means for holding the gangs against relative angular movement including a release means mounted on the front gang, draft means 5 connecting the tractor and a point on one gang on one side of the connection of the gangs and a point on the other gang on the other side of the connection of the gangs, and means for actuating the release means by a movement of the 10 tractor to allow the gangs relative angular movement.

18. In combination, a forward tool, a rearward tool, means forming a connection between the tools to permit relative movement, means holding the tools against relative movement and including a release means mounted on the front tool, draft means, means connecting the draft means and a point on the forward tool on one side of the connection between the tools and a point on the rearward tool on the other side of the connection between the tools, and means responsive to a turning of the draft means for actuating the release means to permit the tools 20 relative angular movement. 25

19. In combination, a forward tool, a rearward tool, means forming a connection between the tools, draft means, hitch means connecting the draft means and a point on one tool on one side of the connection between the tools and a point on the other tool on the other side of the connection between the tools, means for holding the tools against movement with respect to the hitch means including a release means mounted on the front gang, a control device on the draft means, and means responsive to a movement of the control device beyond a certain point for actuating the release means. 30 35

20. A tractor-operated ground-working implement comprising forward and rearward gangs 40 of ground-working tools, means interconnecting the gangs for relative angling movement in a horizontal plane, draft means flexibly connected to the tractor and to both gangs, being connected to the forward gang at one side of the gang 45 interconnection and to the rearward gang at the other side of the interconnection, means for holding the gangs against relative angling movement including a release means mounted on the front gang, and an angling control member connected to the tractor and to the release means and the forward gang adjacent the release means and operative upon turning of the tractor to actuate the release means to permit the gangs 50 relative angling movement and to exert a pull on the front gang to permit the gangs to follow the tractor in making a turn. 55

21. A tractor-operated ground-working implement comprising forward and rearward gangs 60 of ground-working tools, means interconnecting the gangs for relative angling movement in a horizontal plane, draft means flexibly connected to the tractor and to both gangs, being connected to the forward gang at one side of the gang 65 interconnection and to the rearward gang at the other side of the interconnection, an angling control member connected to the tractor at a point offset laterally from the point of draft connection thereto and to the forward gang at a point offset laterally to the last mentioned side of the gang interconnection, means for holding the gangs against relative angling movement and including a release means mounted on the front 70 75

- gang, and means connecting the angling control member and the release means.
22. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, an angling control member connected to the tractor at a point offset laterally from the point of draft connection thereto and to the forward gang at a point offset laterally to the last mentioned side of the gang interconnection, means for holding the gangs against relative angling movement and including a release means mounted on the front gang adjacent the point of connection of angling control member to the front gang, and means connecting the angling control member and the release means.
23. In combination a disk harrow comprising two gangs connected for relative horizontal angular movement, draft means for drawing the harrow, means connecting the draft means and a point on one gang on one side of the connection of the gangs and a point on the other gang on the other side of the connection of the gangs, means for holding the gangs against relative horizontal angular movement and including release means mounted on the front gang, and means connecting the draft means and the release means and a point on the front gang adjacent the release means and responsive to turning of the draft means for actuating the release means and for shifting the gangs for turning.
24. A tractor-operated ground-working implement comprising forward and rearward gangs of ground-working tools, means interconnecting the gangs for relative angling movement in a horizontal plane, draft means flexibly connected to the tractor and to both gangs, being connected to the forward gang at one side of the gang interconnection and to the rearward gang at the other side of the interconnection, means for holding the gangs against relative angling movement, said means including a release means mounted on the front gang, and means connecting the release means and the tractor at a point offset laterally from the point of draft connection and extending in a relatively direct line between the release means and the said offset point on the tractor thereto for causing a turn of the tractor away from the side to which the said point is laterally offset from the draft connection to cause the release means to release the holding means to permit relative angling movement between the gangs.
25. In combination, a disk harrow comprising two gangs connected for relative horizontal angular movement, draft means for drawing the harrow, means connecting the draft means and the front gang on one side of the connection of the gangs and the rear gang on the other side of the connection of the gangs, means for holding the gangs against relative horizontal angular movement and including release means mounted on the front gang to the same side of the connection of the gangs as the connection between the draft means and the rear gang, and means connecting the draft means and the release means and a point on the front gang adjacent the release means and responsive to turning of the draft means for actuating the release means and for shifting the gangs for turning.
26. In combination, a disk harrow comprising two gangs connected for relative horizontal angular movement, draft means for drawing the harrow, means connecting the draft means and a point on one gang on one side of the connection of the gangs and a point on the other gang on the other side of the connection of the gangs, means for holding the gangs against relative horizontal angular movement and including release means acting directly on the front gang, and means connecting the draft means and the release means and responsive to turning of the draft means for actuating the release means.
27. A tractor-operated ground-working implement comprising forward and rearward gangs of ground-working tools, means interconnecting the gangs for relative angling movement in a horizontal plane, draft means flexibly connected to the tractor and to both gangs, means for holding the gangs against relative angling movement including a release means composed of disengageable parts acting directly on the forward gang, and an angling control member connected to the tractor and to one of the disengageable parts of the release means and the forward gang adjacent the release means and operative upon turning of the tractor to actuate the release means to permit the gangs relative angling movement and to exert a pull on the front gang to permit the gangs to follow the tractor in making a turn, said angling control member and release means being positioned on the same side of the point about which angular turning movement takes place between the gangs.
28. In combination, a disk harrow comprising two gangs connected for relative horizontal angular movement, draft means for drawing the harrow, means connecting the draft means and both gangs, means for holding the gangs against relative horizontal angular movement and including release means composed of disengageable parts acting directly on the front gang, and means extending along a line between the draft means and directly connected to one of the disengageable parts of the release means and responsive to turning of the draft means for actuating the release means and for shifting the gangs for turning.

JACOB V. DYRR.
